FIG. 1 is a perspective view of a stand-up counterbalance lift truck as seen from the top, rear and left sides of the truck showing our new design;

FIG. 2 is a perspective view seen from the top, rear and left sides thereof;

FIG. 3 is a perspective view seen from the top, front and right sides thereof;

FIG. 4 is an elevational view seen from the front thereof;
FIG. 5 is an elevational view seen from the rear thereof;
FIG. 6 is an elevational view seen from the right side thereof;

FIG. 7 is an elevational view seen from the left side thereof; and,

FIG. 8 is a plan view seen from the top thereof.

The broken line showing of some elements in FIG. 1 is included for the purpose of illustrating environment and forms no part of the claimed design.
